Inventor:
Catherine Whitney

UNITED STATES PATENT OFFICE.

CATHERINE WHITNEY, OF LAWRENCE, KANSAS.

MANGLE.

SPECIFICATION forming part of Letters Patent No. 329,250, dated October 27, 1885.

Application filed May 31, 1884. Serial No. 133,409. (No model.)

To all whom it may concern:

Be it known that I, CATHERINE WHITNEY, a citizen of the United States, residing at Lawrence, in the county of Douglas and State of Kansas, have invented a new and useful Improvement in Wooden Clothes-Mangles, of which the following is a description.

This invention relates to that class of mangles in which large wooden rollers are used for smoothing clothes, and its object is to provide means whereby a receptacle for the clothes to be ironed and another receptacle for the clothes which have been ironed may both be convenient to the mangle, and means whereby the weight of the said receptacles and the clothes therein contained may be utilized to assist in the ironing process.

To this end my invention consists in the construction and combination of parts forming a clothes-mangle, hereinafter described and claimed, reference being had to the accompanying drawings, in which—

Figure 1 is a side elevation of my mangle. Fig. 2 is an end elevation, and Fig. 3 is a plan view of the same.

J represents the ironing-table, supported on legs K.

I represents two vertical posts, one at each end of the table, rigidly secured thereto, and projecting above it as bearings for pulleys A and D.

G G are two rollers, made smooth and true, to roll upon the table J. Around these rollers the clothes are wrapped to be ironed in the manner usual to this class of machines.

To aid in ironing, I provide an upper board in the form of a box, L, which is made a true plane on its under side to travel upon the rollers G, to press the latter down upon the clothing, and to smooth the clothing upon the rollers as it comes up over them.

C is a rope passing like a belt over the pulleys A and D, and secured at its ends to the box L, whereby a reciprocating circular motion of the pulley A draws the box to and fro over the table on the rollers G. Motion is given to the pulley A by a hand-crank, B, which is connected with the axle thereof. The posts I are located at the centers of the ends of the table in order that the longitudinal sides thereof may be open and unobstructed for the management of the work.

E and F are compartments in the box L, in one of which the clothes to be ironed may be placed, and as fast as they are ironed they may be placed in the other. When the ironing is large, no further weight is necessary to cause the box to press hard enough upon the rollers to do the work of smoothing or ironing the clothes, yet I have provided another compartment, N, into which any weight may be placed, if necessary, and be kept separate from the clothes in order not to soil them.

Z represents hinges, and g knobs to the lids of the compartments E and F.

What I claim as my invention, and desire to secure by Letters Patent, is—

In a clothes-mangle, the combination, with the table, the posts secured about centrally of the ends of the table, and the pulleys, one supported in each post, and one having a crank, of the rollers resting upon the table, the box superposed upon the rollers, and the rope passing over one pulley and rove around the other, the crank-operated pulley, the ends of said rope being connected to one edge of said box, substantially as shown and described, and for the purpose set forth.

CATHERINE WHITNEY.
